UNITED STATES PATENT OFFICE.

RICHARD F. HAMILTON AND DAVID LIPSICH, OF NEW YORK, N. Y.; SAID LIPSICH
ASSIGNOR TO SAID HAMILTON.

SHEET-METAL BOX OR TRAY.

1,148,015.

Specification of Letters Patent. Patented July 27, 1915.

Application filed December 18, 1912, Serial No. 737,549. Renewed June 16, 1915. Serial No. 34,561.

To all whom it may concern:

Be it known that we, RICHARD F. HAMILTON and DAVID LIPSICH, citizens of the United States of America, residing at New York city, borough of Manhattan, county and State of New York, and New York city, borough of Brooklyn, county of Kings, and State of New York, respectively, have invented certain new and useful Improvements 5 in Sheet-Metal Boxes or Trays, of which the following is a specification.

Our invention relates to metal receptacles for holding and carrying bottles and the like. Boxes or trays of this kind having two 15 series of partitions arranged at right angles to form one or two dozen compartments for the reception of bottles containing beer, mineral water and the like, have heretofore usually been made of wood. These are 20 structible and are frequently stolen or appropriated for kindling wood and other purposes in the cities, and the owners' names scraped off. We have invented a box or tray of this character which is made solely of 25 sheet metal without rivets or stiffening rods, and is yet strong and compact, together with a rack for supporting and separating the bottles.

The best forms of our invention at present 30 known to us are illustrated in the accompanying three sheets of drawings in which,

Figure 1 is a general plan of the box, with parts broken away and shown in section. Fig. 2 is an enlarged detail vertical section 35 taken on line 2—2 of Fig. 1. Fig. 3 is a detail side elevation of one of the longitudinally extending strips forming the compartments in the box. Fig. 4 is a similar view of one of the transversely extending 40 strips, and Figs. 5 and 6 show modifications.

Throughout the drawings like reference characters indicate like parts.

The shell of the box is preferably formed of two sections of sheet metal, such as galvanized iron or sheet steel or tin plate. 45 Each of such sections 1 and 2 is bent at right angles so as to form one end and one side of the box and the abutting ends are soldered or welded, or otherwise fastened 50 together. In one form shown in Figs. 1 and 2, the upper edge of each sheet is bent inwardly and downwardly and outwardly

to form the semicircular bead 3, and the horizontally extending flange 4 below the same. This construction stiffens the top of 55 the box and also, as the hand hole 5 in each end of the box is formed adjacent to the lower flange 4, such flange and bead form a finished handle to be grasped by the hand of the person who lifts the box, inserted 60 through the hand hole. A portion of the metal 23, stamped out to form the hand hole 5 may be folded into flange 4, as shown in Fig. 2. Each of the metal sheets is bent inwardly and upwardly and backwardly 65 along the bottom to form the bottom ledge or flange 6, a slot being left between the inner edge of this flange and the shell of the box. The metal sheets are also bent inwardly along a line extending around the 70 box, preferably approximately half way between the top and the bottom, to form a V-shaped rib 7, which projects inwardly. This rib serves to further stiffen the box and also affords convenient means for attachment 75 of the inner rack hereinafter to be described.

While the above described construction is recommended by us in cases wherein heavy and stiff metal sheets can be used, we find 80 that when metal sheets of such thickness as to be easily bent are used, the bead 3 and flange 6 are too easily indented and when such lighter material is used we prefer the form shown in Fig. 6. In such case the top 85 of the metal sheets forming the sides and ends of the box are reinforced by a bent strip 24 of much heavier metal which is clamped thereon and has a horizontally projecting flange 25. The portion of metal 90 23 stamped out to form the hand hole in the end of the box may lie up along the under side of the horizontal flange 25 in a manner similar to that described and shown in Fig. 4 with reference to flange 4. In this form 95 of our invention the bottom portion of the metal sheets forming the box are bent into the S-form shown at 26, or other convenient form to receive and hold a strip of heavy metal 27 bent into U-shaped cross-section to 100 form a shoe on which the box rests.

In the form shown in Fig. 5, the semicircular bead around the top of the box is also employed as shown at 30, but it is dropped

below the upper edge of the box somewhat, and the doubled portion 31 of the metal forms a guard to partly protect the bead from blows delivered by objects falling on 5 top of the box. At the bottom, a doubled strip of sheet metal 32 is shown inserted in one recess of the S-shaped cross section into which the lower edges of the sheets forming the box walls are again bent.

10 The rack used with all of these forms of box-like shell formed by the assembling of sections 1 and 2 is composed of a series of longitudinally extending partition strips 8, 8, and another series of transversely extending 15 partition strips 9, 9. One series of strips, as 8, 8, are slotted inwardly from one edge, as at 14, and the other series of strips 9, 9, are correspondingly slotted inwardly from their other edges, as at 15. When the 20 two sets of strips are interlocked by slipping the slotted portions together a series of compartments are formed between these partitions in the well known manner, and if the strips 8 and 9 are properly fastened together 25 a rack is formed thereby. To conveniently fasten the strips together and also serve the purposes hereafter to be pointed out, we bend the upper and lower edges of the strips 8 and 9 to form horizontally extending 30 flanges on either side, 10 being the top flange and 11 the bottom flange in each strip. The ends of the strips 8, 8, are cut and bent to form the short laterally extending flanges 18, 18, and the outwardly extending lugs 12, 35 which latter consist of projecting portions of the metal which has been bent to form the top flange 10. In the same way flanges 19 and outwardly projecting lugs 21 are formed on the strips 9. The projecting portions of the strips 8, 8, which have been 40 folded over to form the bottom flange 11, are bent downwardly at right angles to form lugs 13 and similar lugs at the bottom of strips 9, 9, are formed as shown at 22. The 45 flanges of the strips 8 and 9, which are cut in producing the slots 14 and 15, are bent outwardly, as shown, to form the short lugs 16 and 17. The uncut flanges of these strips 8 and 9 are slotted to receive these lugs 16 and 17, when the strips are assembled, and 50 interlocked to form the rack. The ends of the lugs are then bent over, as shown in Figs. 1 and 2, to clench the parts together. The dotted circles 20, 20, represent the outline of bottles or other cylindrical objects 55 set in the compartments in the rack in the tray or box.

The mode of making and using our invention is as follows: The strips 8 and 9, forming 60 the partitions, being interlocked and clenched together, as above described, to form the rack, are placed in the box or shell formed by assembling the two sheet metal

sections 1 and 2. The upper outwardly projecting lugs 12 and 21 are passed through 65 slots formed in the apex of the V-shaped rib 7 and bent or spread outwardly, as shown in Fig. 2, to clench the connection and the bottom lugs 13 and 22 are hooked over the ledge 6 or equivalent construction shown in other 70 figures of drawing at the bottom of the box, thus securely fastening the rack in position in the shell or box. The bottom flanges 11 of the strips are made wide enough, as 75 shown in Fig. 1, to extend part way under the bottoms of the bottles or other circular objects placed in the compartments and support the same. The top flanges 10 are bent downwardly at the points 50 intermediate of the intersections of the strips 8 and 9, 80 as shown in Figs. 1 and 2, so as to form an approximately circular upper opening for the compartments into which the bottles may fit.

The advantages of our invention comprise 85 its lightness, stiffness and durability resulting from the fact that it is made wholly of sheet metal bent and folded so as to produce stiffening means and ample interlocking portions. There are no metal rods to 90 rust or produce friction which will wear through the adjacent metal sheet. The bottom flange or ledge 6, or shoes 27 and 32 form a smooth stiff rib upon which the box 95 may be freely shoved around on the floor without catching or bending and this, together with the top bead or metal reinforcement and flange and the intermediate V-shaped rib give the box ample stiffness 100 against twisting and bending strains.

Having described our invention we claim:

1. An interlocking set of metal strips for dividing a box into a series of compartments which strips are slotted so as to interlock one with another, and have their upper and lower edges bent at right angles to form flanges, one flange of each strip being slotted at each junction point and the corresponding flange of the crossing strip being cut and bent to enter said slots, whereby the two sets may be fastened together by bending over the portions projecting through said slots. 105

2. A sheet metal box for carrying bottles and the like formed without a bottom, but having longitudinally and transversely extending partitions formed of interlocking metal strips, said strips being folded along their lower edges to form horizontally extending flanges on either side which extend 110 part way under the bottoms of the bottles set in the compartments formed by said partitions, said strips having the flanges along their upper edges reduced in width by bending downward at points intermediate of the 115 intersections, whereby an approximately cir- 120

cular upper opening is formed for each compartment.

3. A rack formed of two sets of strips cut part way through to permit them to interlock, said strips having their edges bent over to form horizontal flanges, the flanges on the uncut side of each strip being slotted in line with the cut on the other side, and the cut ends of the flange on the cut side of each

strip being bent outwardly to engage the 10 slots in the adjacent flange of the other strip when the strips are assembled to form the rack.

RICHARD F. HAMILTON.
DAVID LIPSICH.
